UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN-ROD BRACKET.

Application filed June 5, 1926. Serial No. 113,846.

This invention relates to improvements in brackets for supporting curtain rods, and in its chief intended application is designed to serve as an intermediate supporting bracket for a plurality of comparatively long curtain rods of the flat telescoping type. In Letters Patent No. 1,424,337 granted to me August 1, 1922, I have disclosed a curtain fixture of the general type referred to, wherein a pair of rods are centrally supported by a bracket consisting of an arm comprising upper and lower flat metal strips riveted together with their inner ends bent to form an attachment member and their outer 5 ends bent downwardly and spaced one in front of the other and terminating in upturned lips to support the lower edges of the curtain rods, each of the strips also having an integral spring tongue cut therefrom 10 with its free end bent downwardly to form a hook or detent engageable over the upper edge of the rod; the bracket above-described being very clearly shown in Figs. 3 and 15 4 of my aforesaid patent.

My present invention is in the nature of an improvement upon the intermediate rod-supporting bracket of the aforesaid patent. In the use of the said bracket, the rod, with the curtain or drape suspended therefrom, 20 is engaged with the bracket by a lateral thrust on the rod, the lower edge of the latter being first seated in the lip of the bracket arm, and the upper edge being then engaged with the hook or detent by 25 an inward thrust on the latter which first raises the hook and then permits the latter to snap down over the upper edge of the rod. Where, as in the aforesaid bracket, the two rod seats or sockets are permanently 30 fixed one in front of the other, it is a matter of some difficulty to enter the rod, with the curtain thereon, into the rear seat of the bracket, since the front seat is somewhat in the way; and moreover, during such 35 mounting of the rear rod and the hem of the curtain in the rear seat, the detent or hook on the spring tongue tends to roll or twist the ruffle on the upper edge of the curtain forwardly and downwardly, causing 40 the latter to present a somewhat unsightly 45 appearance.

The main object of the present invention is to provide a practical improvement upon the bracket of my aforesaid patent in the 50 directions of, first, facilitating the operation

of seating the rod and the hem and ruffle of the curtain in the rear lying seat or seats of the bracket, and, second, of enabling the hem and ruffle of the curtain to be easily adjusted to normal correct position at the 55 time the rod is inserted. My present invention may be embodied in a bracket having two, three or more arms for supporting a corresponding number of rods, and the invention, broadly stated, resides in providing a pivotal connection of each arm (except the lowermost) at its rear end on the next underlying arm, so that, when the rearmost rod is to be seated in the lowest arm of the bracket, the overlying arm or arms may 60 be swung up entirely out of the way, and, similarly, when the next to the rearmost rod is to be entered into its arm of the bracket, the arm or arms thereabove may be similarly 65 swung up and out of the way, and so on until all except the front rod have been 70 engaged with their respective seats.

My invention, in one simple and practical form in which it may find embodiment, is 75 illustrated in the accompanying drawings, 80 in which—

Fig. 1 is a side elevation of a curtain rod-supporting bracket adapted for use with three parallel rods;

Fig. 2 is a similar view of the same 85 bracket showing the top and intermediate arms swung upwardly to facilitate the seating of the rear rod in the lowermost arm;

Fig. 3 is a similar view showing the topmost arm swung up to facilitate the seating 90 of the intermediate rod;

Fig. 4 is a top plan view of Fig. 1; and

Fig. 5 is a front elevation, viewed from the bottom of Fig. 4.

Referring to the drawings, 10 designates 95 a flat metal strip constituting the lowermost arm of the bracket and having its rear end portion 11 bent upwardly to form an attaching member by which it may be secured to a window frame F by screws 12. At its 100 forward end the arm 10 has a downwardly bent substantially vertical portion 13, terminating at its lower end in an upwardly curved lip 14 which forms a seat for the lower edge of the rearmost curtain rod A. 105 From the strip 10 is cut a central longitudinally extending tongue 15 which extends forwardly through a central vertical slot 16 (Fig. 5) in the downwardly bent portion 13 and overhangs the lip 14 and at its for- 110

ward end is formed with a downwardly bent 65
detent 17 adapted to snap over the upper
edge of the rod A to thereby hold the latter
engaged with the bracket. This lowermost
5 arm 10 is formed on its opposite edges and
a short distance forwardly of its attaching
base 11 with a pair of integral hinge pintles
18, conveniently formed by notching out the
edge of the arm on either side of the pintle;
10 and mounted to swing on the hinge pintles
18 is an overlying bracket arm 10' formed at
its rear end with a pair of eyes 19 engaged
with the pintles 18 and in all other respects
15 identical with the arm 10; the forward rod-
engaging portion of the arm 10' lying in
front of and slightly above the correspond-
ing portion of the arm 10, and serving to
support the intermediate rod B.

The bracket as thus far described is com-
20 plete for service in connection with two rods.
Where the fixture includes three rods, as
is sometimes the case, the same structural
principle is extended to provide a third
25 arm 10^a in all respects identical with the
intermediate arm 10', said arm 10^a being
hinged to the arm 10' by eyes 19' engaged
with pintles 18', said arm serving to sup-
port a third front rod C.

The manner of mounting the three rods
30 in the above-described bracket is progres-
sively illustrated in Figs. 2, 3 and 1. The
bracket having been attached to the window
frame, and the rod A having been passed
35 through the hem of the curtain, the upper
and intermediate arms 10^a and 10' are
swung upwardly and rearwardly, and the
rod A with the curtain thereon is pressed
40 into its seat on the forward end of arm 10.
This having been done, the twisting or other
dislocation of the top edge of the hem and
the ruffle caused by the detent 17 can be
45 easily corrected by thrusting the detent up-
wardly by the thumb or finger. The inter-
mediate arm 10' is then lowered, leaving the
topmost arm 10^a in raised position, and the
rod B, usually carrying a drape, is mounted
50 and the upper end of the drape adjusted
in the same manner. The topmost arm 10^a
is then lowered, and the third rod C, usually
carrying side drapes, is similarly mounted,
55 and the upper ends of the side drapes ad-
justed to correct form.

From the foregoing it will be seen that
55 the above-described multiple rod bracket
consisting of relatively hinged sections each
supporting one rod, all except the lowermost
of which can be swung up and out of the
way to permit the successive seating of the
60 rods, considerably facilitates the mounting
of the rods in the bracket and the proper
adjustment of the upper edge or ruffle of
the curtain, thereby effecting the stated pur-
poses of the invention. When the curtain
65 and drapes are hung, the weight of the

bracket arms, rods and curtain and drapes 65
easily maintains the rods in normal correct
position. Furthermore, simplicity of man-
ufacture and economy of cost are greatly
promoted by the simple expedient of form-
ing the hinge elements from the metal of 70
the arms themselves.

While I have herein shown one simple
and efficient embodiment of the principle
of the invention, manifestly the structural 75
details disclosed may be variously modified
within the purview of the invention and
without sacrificing any of the benefits and
advantages secured thereby. Hence, I do
not limit the invention to the specific struc-
80 tural form herein disclosed for purposes of
illustration, but reserve all such variations,
modifications and mechanical equivalents as
fall within the spirit and purview of the
claims.

I claim—

1. A supporting bracket for a plurality
of curtain rods, comprising a plurality of
bracket arms hinged to each other to swing
in a vertical plane and provided respectively
85 with rod-engaging seats at their forward
ends disposed one in front of another in
the lowered position of said arms.

2. A specific form of claim 1, wherein
the hinge elements of said bracket arms
are formed as integral parts of the arms 95
themselves.

3. A supporting bracket for a plurality
of curtain rods, comprising a bracket arm
formed at its forward end with a rod-en-
gaging seat and at its rear end with an 100
attachment member, and an overlying arm
hinged at its rear end on said first-named
arm to swing upwardly and rearwardly and
formed at its forward end with a rod-en-
gaging seat lying in advance of said first- 105
named seat.

4. A specific form of claim 3, wherein
said first-named bracket arm is formed with
integral hinge pintles on its opposite edges,
and said overlying arm is formed at its rear 110
end with eyes engaged with said pintles.

5. A supporting bracket for a plurality
of curtain rods, comprising a bracket arm
formed at its forward end with a rod-en-
gaging seat and at its rear end with an 115
attachment member, an intermediate arm
overlying and hinged at its rear end on said
first-named arm to swing upwardly and
rearwardly and formed at its forward end
with a rod-engaging seat lying in advance 120
of said first-named seat, and a top arm over-
lying and hinged at its rear end on said
intermediate arm to swing upwardly and
rearwardly and formed at its forward end
with a rod engaging seat lying in advance 125
of said first and second-named seats.

JAMES H. BOYE.
